FISHING LURE

Roger Cauquis, 25 Rue de la Prairie,
93 Aulnay, France

Filed June 15, 1973, Ser. No. 370,405

Term of patent 14 years

Int. Cl. D22—05

U.S. Cl. D22—27

Fig-1

Fig-2

Fig-4

Fig-3

Fig-5

Fig-6

FIG. 1 is a perspective view of a fishing lure, embodying my new design;

FIG. 2 is a top plan view thereof;

FIG. 3 is a side elevation view thereof, the opposite side being substantially the mirror image thereof;

FIG. 4 is a front elevation view thereof;

FIG. 5 is a rear elevation view thereof; and

FIG. 6 is a bottom view thereof.

I claim:

The ornamental design for a fishing lure, as shown and described.
